UNITED STATES PATENT OFFICE.

CHARLES MCKERAHAN, OF ALLEGHENY, PENNSYLVANIA.

DESIGN FOR AN INKSTAND.

SPECIFICATION forming part of Design No. 20,211, dated October 21, 1890.

Application filed September 24, 1890. Serial No. 366,027. Term of patent 7 years.

To all whom it may concern:

Be it known that I, CHARLES MCKERAHAN, a citizen of the United States, residing in Allegheny city, in the county of Allegheny and State of Pennsylvania, have invented and produced a new and original Design for Inkstands, of which the following is a specification, reference being had to the accompanying drawing, forming a part of this specification, which represents in perspective an inkstand embodying my new and original design.

The leading feature of my design consists in the ornamental body of the inkstand, the same presenting in its general contour an anvil-like figure, and the pen-rack presenting the appearance of a pair of antlered horns.

A is the body of the inkstand; B, its cover, and C the pen-rack. The body A comprises a base *a* and top *a'*, the lines of the top ex-

tending laterally beyond the base *a*, and the whole constituting an anvil-like figure. At the front of the body is a button-like figure *a''*.

The cover B presents a rectangular figure approximating in its general contour the main portion of the upper surface of the body A, and has a stud-like figure *b*, the lines of which depart from the under surface of said cover.

The pen-rack C presents a figure representing antlered horns, the lines of the figure departing in an upward and outward direction from the body A at the rear of the upper surface of said body.

I claim—

The design for an inkstand herein shown and described.

CHARLES MCKERAHAN.
